LIQUID FUEL BURNER

Reginald W. Beckett, Cleveland, Ohio, assignor
to The Timken Silent Automatic Company, De-
troit, Mich., a corporation of Michigan

Application September 26, 1932, Serial No. 634,811

12 Claims. (Cl. 158—4)

My invention relates to liquid fuel burners of the type wherein combustion takes place around the walls at the periphery of a hearth to which liquid fuel is sprayed by a centrally disposed rotary distributor head. The invention has for its principal object a construction wherein initial propagation of the flame around the entire burner periphery is quickly accomplished and wherein the liquid fuel is effectively vaporized or gasified 5 and entirely consumed with a very hot and quiet flame.

My invention consists principally in providing the liquid fuel burner with a peripheral ignition and combustion ring of refractory material comprising an inner wall having a multiplicity of openings therethrough and an outer or rear wall spaced therefrom, said rear wall being provided with lugs, the sides of said fingers and said lugs being ribbed or corrugated to increase the area 15 of refractory material in contact with the gasified fuel. The invention further consists in the liquid fuel burner and in the combinations and arrangements of parts hereinafter described and claimed.

25 In the accompanying drawing, which forms part of this specification and wherein like reference numerals refer to like parts wherever they occur,

30 Fig. 1 is a partial sectional view of a liquid fuel burner embodying my invention.

Fig. 2 is a partial top plan view.

Fig. 3 is a sectional view on the line 3—3 in Fig. 2, and

35 Fig. 4 is a side elevation of a segment of the hearth ring.

In the drawing is illustrated a liquid fuel burner of the type commonly designated as rotary wall flame, including a central rotary distributor head 1 that discharges liquid fuel and air in substantially separate layers, a hearth 2 of refractory material and an ignition and combustion ring 3 of refractory material extending around the periphery of the hearth in contact with the water leg 4 or furnace wall. Ignition and combustion 40 take place around the periphery of the hearth, a suitable ignition means, as a gas pilot light 5 being provided. The peripheral ring 3 is provided with an oil collecting gutter 6 around its inner edge, the face 7 of the ring behind said gutter forming an impact wall for the liquid fuel and air. When the burner is started, oil sprayed 45 against the ring is partly broken up and vaporized, but for the most part drips down into said gutter 6, where it is ignited and the flame propagated around the entire ring. As the ring becomes heated, the liquid fuel is vaporized more and more completely and the flame rises to the top of the ring 3 until, under normal operating conditions, there is no collection of oil in the gutter 50 and the flame is located entirely above the

top of said ring. The present invention is concerned with the details of construction of said ignition and combustion ring. The combustion ring 3 is provided with a deep annular channel 8 in its upper surface. Upstanding fingers 9, whose upper ends are preferably provided with concavities 10, form the inner wall of said channel, the openings between fingers 9 permitting passage of air and vaporized fuel into said channel 8. Projecting upwardly from the rear or outer portion of the ring 3 is a sloping wall 11 that is provided with projecting lugs 12 that may be disposed opposite said fingers, the inner or front faces of said lugs being substantially vertical. The upper edges of said wall 11 and of 15 said lugs 12 are preferably provided with concavities 13.

The side faces of said fingers 9 and of said lugs 12 are provided with a multiplicity of ribs 14 thus greatly increasing the surface thereof; 20 and the portions of the ring between said fingers 9 and of the wall 11 between said lugs 12 are also provided with ribs 15. The surface of the ring between said fingers 9 slopes downwardly 25 towards said channel 8.

When the burner is started, the oil strikes said impact wall 7 and for the most part drips down into the ignition gutter 6, a comparatively small part being vaporized. Ignition and propagation of the flame around the gutter take place as above 30 described. As the ring becomes heated, the liquid fuel is entirely vaporized or gasified and the flame gradually works its way to the top of the ring. The deep channel 8 in the ring 3 tends to create a low pressure condition that prevents the flame 35 from pulling away from the top of the ring: part of the air draft and part of the gasified fuel pass into the spaces between the fingers 9 and the lugs 12 and move upwardly through the deep channel 8 and up the inclined outer wall. Mixture and 40 combustion take place at reduced velocities, thus preventing lifting of the flame.

While not necessary to the satisfactory operation of the burner, the ribs increase the surface of the ring in contact with the fuel, and thus 45 bring about more efficient vaporization of the liquid fuel and, becoming highly heated, provide very quick combustion. The separation of the fingers 9 from the back wall 11 reduces the heat loss through the fingers thus allowing them to 50 reach higher temperatures with consequent more rapid vaporization of the liquid fuel.

Preferably, the ignition and combustion ring is made of individual segments and is set so that 55 the ignition gutter is below the level of the hearth, but it may be set so as to raise the gutter and provide a step protecting the gutter from the main draft of air. The segments may be made for round or rectangular boilers.

What I claim is:

1. A liquid fuel burner construction comprising a refractory hearth, a rotary distributor head for liquid fuel and air at the center of said hearth and an ignition and combustion ring around the periphery of said hearth, said ring having a deep annular channel therein, the inner wall of said channel having a multiplicity of openings therethrough to permit passage of air and vaporized fuel into said channel, said ring having an imperforate portion beneath and flush with said inner wall of said channel constituting an impact wall.
2. A liquid fuel burner construction comprising a refractory hearth, a rotary distributor head for liquid fuel and air at the center of said hearth and an ignition and combustion ring around the periphery of said hearth, said ring having a deep annular channel therein, the inner wall of said channel having a multiplicity of openings therethrough to permit passage of air and vaporized fuel into said channel, and the outer wall of said channel having a multiplicity of inwardly projecting lugs.
3. A liquid fuel burner construction comprising a refractory hearth, a rotary distributor head for liquid fuel and air at the center of said hearth and an ignition and combustion ring around the periphery of said hearth, said ring comprising an inner wall having upwardly projecting fingers, and an outer wall, and said outer wall being provided with lugs upon its inner face.
4. A liquid fuel burner construction comprising a refractory hearth, a rotary distributor head for liquid fuel and air at the center of said hearth and an ignition and combustion ring around the periphery of said hearth, said ring having upwardly projecting fingers around its inner face and an outer wall, said outer wall being provided with inwardly extending lugs opposite said fingers.
5. A liquid fuel burner construction comprising a refractory hearth, a rotary distributor head for liquid fuel and air at the center of said hearth and an ignition and combustion ring around the periphery of said hearth, said ring having upwardly projecting fingers around its inner face and an outer wall, said outer wall being provided with inwardly extending lugs opposite said fingers, said wall and the upper surface of said ring between said fingers both sloping towards the bottom of the annular space between said fingers and said lugs.
6. A liquid fuel burner construction comprising a refractory hearth, a rotary distributor head for liquid fuel and air at the center of said hearth and an ignition and combustion ring around the periphery of said hearth, said ring having an oil collecting gutter around its inner periphery, an inner wall with openings therethrough and an outer wall, said inner and outer walls being spaced apart to form a deep annular channel around said ring, the lower portion of said inner wall constituting an imperforate impact wall around the outer periphery of said gutter.
7. A liquid fuel burner construction comprising a refractory hearth, a rotary distributor head for liquid fuel and air at the center of said hearth and an ignition and combustion ring around the periphery of said hearth, said ring having an oil collecting gutter adjacent its inner periphery,

an inner wall with openings therethrough and an outer wall, said inner and outer walls being spaced apart to form a deep annular channel around said ring, said outer wall being provided with lugs extending from its inner face.

8. A liquid fuel burner construction comprising a refractory hearth, a rotary distributor head for liquid fuel and air at the center of said hearth and an ignition and combustion ring around the periphery of said hearth, said ring having an oil collecting gutter around its inner periphery, upwardly projecting fingers around its inner face and an outer wall, said outer wall being provided with lugs projecting inwardly from its inner face, the side faces of said fingers and of said lugs being provided with a multiplicity of ribs.

9. A liquid fuel burner construction comprising a refractory hearth, a rotary distributor head for liquid fuel and air at the center of said hearth and an ignition and combustion ring around the periphery of said hearth, said ring having an oil collecting gutter around its inner periphery, upwardly projecting fingers around its inner face and an outer wall, said outer wall being provided with lugs projecting inwardly from its inner face, the sides of said fingers and of said lugs being provided with a multiplicity of ribs, and the tops of said fingers and of said lugs being provided with concavities.

10. A liquid fuel burner construction comprising a refractory hearth, a rotary distributor head for liquid fuel and air at the center of said hearth and an ignition and combustion ring around the periphery of said hearth, said ring having an oil collecting gutter adjacent its inner periphery, upwardly projecting fingers around its inner face and an outer wall, said outer wall being provided with lugs projecting from its inner face opposite said fingers and forming therewith a deep annular channel, the portions of said wall between said lugs and the portions of the ring between said fingers sloping towards the bottom of said channel.

11. In combination with means forming a combustion chamber having a hearth closing in the bottom thereof, fuel and air distributing mechanism disposed within said chamber adjacent the hearth and designed to project liquid fuel and air in separate layers over the hearth surface, and an upright structure disposed directly upon said hearth adjacent the wall of the combustion chamber in relatively remote relation to said distributing mechanism and designed to intercept, mix and burn the separate fuel and air layers projected by the latter; said upright structure comprising a pair of substantially vertical walls that are substantially normal to the path of fuel projection and that are relatively spaced in the direction of said path to form a deep channel closed at the bottom thereof and having communication with the combustion chamber.

12. In the combination defined in claim 11, said communication being by way of the top of the channel, and the upper portion of the innermost wall of the pair having a plurality of passages establishing further communication in the general direction of the path of fuel and air projection, the innermost wall of said pair having an imperforate portion forming an impact surface for the liquid fuel.

REGINALD W. BECKETT.
